SEDWICK N. WIGHT, OF ROCHESTER, NEW YORK, ASSIGNOR TO GENERAL RAILWAY SIGNAL COMPANY, OF ROCHESTER, NEW YORK

TRAIN-DISPATCHING SYSTEM FOR RAILROADS

Application filed September 21, 1927. Serial No. 221,037.

This invention relates to train dispatching systems, and more particularly to means for indicating the approach of a train within a limited distance of a track switch or other traffic controlling device.

In dispatching the movement of trains on a railway system, and this is true of either single or double track systems, it is desirable to indicate to a local dispatcher or operator when a train has come within a certain distance, say one mile, of the track switch at the end of the distant siding, of a derail, or the like. It is also desirable to be able to control a switch machine for operating such distant track switch or derail to control the signals associated therewith, and to indicate the passage of a train over a detector track circuit associated with such track switch, as well as the response of the switch machine to its control from the local dispatcher's office. Further, in the case of a distant switch machine, it is necessary for safety to provide approach locking means to prevent operation of such switch machine in the face of a train approaching at high speed.

In view of the foregoing and other important considerations it is proposed in accordance with the present invention to so associate these circuit portions and devices that all these functions are obtained with a minimum of line wires. More specifically, it is proposed to combine the approach locking features when such are used with the feature of indicating the approach of a train within an appreciable distance of a track switch in such a way that both of these functions are carried out over the same simple (not multiplex) control circuit extending such distance beyond the track switch in question, and to carry out all of the various controls and indications over the same line circuit connecting the local dispatcher's office with such distant track switch. As a further feature it is proposed to not only give a visual indication at the tower as to conditions of traffic and switch machine conditions at the distant track switch, but it is proposed to give a momentary audible indication when an indicating lamp is lighted.

Other objects, purposes and characteristic

features of the invention are in part described in the accompanying specification herein-after, and are in part obvious from the accompanying drawing.

In describing the invention in detail, reference will be made to the accompanying drawing in which:

The single figure shows the invention applied to a single track railroad equipped with absolute-permissive-block signals, and in which the approach of a train from each direction is distinctively indicated.

Structure.—Referring to the drawing the dotted rectangle DO designates a local dispatcher's office in which is contained a miniature track layout, having indicating lamps 4, WL and EL associated therewith, and in which only one lever L, of a bank of levers for controlling distant track switches, derails and signals, has been illustrated. This lever L is adapted to control through the line circuit including the line wire 10 and the common return wire C a distant control relay Z, which line circuit includes the line or indicating relay LR or PA, as the case may be. This line relay LR in combination with the lever L and the conditions of traffic at the distant track switch is adapted to control the indicating lamp 4 and the relay PA is adapted to control the indicating lamps WL and EL.

In the particular track layout shown the main track comprises rails 6 and 7, which through the medium of track switch 1S diverges into the main track having rails 6 and 7 and the side track having rails 8 and 9 of a passing siding. These tracks are divided into sections by insulated joints 11, of which the section adjacent the track switch comprises the usual detector or fouling track circuit including the track battery 12 and the track relay (conventionally shown by a dotted line) 2DT; the next track section toward the right of which has a track circuit comprising track battery 13 and track relay 1T; and the third track section ahead includes the track circuit containing the track battery 14 and the track relay 2T.

The track switch 1S is preferably controlled by switch machine SM, which has

been conventionally illustrated. Since the particular track layout shown is intended to accommodate traffic moving in both directions, that is, consists of a portion of a single track railroad, the main starting signals 2 and 2^a entering signal 1, the take-siding signal 1^a and the distant signals 3 and 4 only are required in the section shown, and have been illustrated. In the arrangement shown there is provided an approach indication relay EA which is normally energized through the following circuit:—beginning at the terminal B of a suitable source of current, front contact 17 of the track relay 3T, wire 18, front contact 19 of the track relay 2T, wire 20, front contact 21 of the track relay 1T, wire 22, winding of the approach indication relay EA, to a common return wire C connected to the other terminal of said source. The relay WA is energized over a similar circuit readily traced and identified by similar reference characters.

With the approach indication relay EA energized the relay EX is energized through the following circuit:—beginning at the positive terminal of the battery 40, wire 41, front contact 42 of the relay EA, wire 43, winding of the relay EX, wire 44, back to the midpoint of the battery 40. The relay WX is energized over a similar circuit readily traced and identified by similar reference numbers. With the relays EX, WX and WP energized the following circuit for the Os-ing relay OS is energized:—beginning at the terminal B, front contact 52 of the relay WP, wire 53, front contact 54, of the relay EX, wire 53', contact 54' of relay WX, wire 55, winding of the relay OS to the common return wire C connected to the midpoint of said battery. In this connection it should be noted that if relay WP is deenergized and the detector track relay 2DT is energized this same circuit is completed from the negative terminal NB of said battery through front contact 56 of relay 2DT and wire 57. It is believed that the structure has now been sufficiently described so that the invention is best understood by considering the operation of the various devices in response to control from the dispatcher's office and the response to the movement of trains obtained.

Operation.—Let us first assume that there is a train approaching from the right, but that this train has not yet reached the signal 3, and that the operator is uncertain as to whether this train is to take the main track or the siding, and for this reason he is waiting to be informed when the train reaches the track circuit containing track relay 3T, so that he can compare this fact with other traffic conditions and may from such comparison determine whether the train in question shall take the main track or the siding. As soon as this train moving from right to left treads upon the track circuit contain-

ing track relay 3T the energizing circuit for the approach indicating relay EA is broken at the front contact 17 of this track relay 3T. Dropping of the relay EA reverses the polarity applied to the relay EX, so that this relay EX is de-energized for a moment, at least while the magnetism of its magnetic circuit goes through zero. Momentary de-energization of the relay EX momentarily de-energizes the relay OS, and momentary de-energization of the relay OS applies current to the line wire 10 leading to the dispatcher's office DO for a moment only through the following circuit:—beginning at the plus terminal of the battery 60, back contact 201 of the relay EX, wire 202, front contact 203 of the relay WA, wire 204, back contact 205 of the relay 2S, wires 206 and 207, back contact 208 of the relay Z, wire 64, front contact 65 of the detector, track relay 2DT, wire 66, back contact 67 of the relay OS, wires 68 and 10, wire 209, winding of the line relay PA, wire 210, contact 211 of the lever L in its neutral position to the common return wire C, which through back contact 72 of relay OS and wire 73 is connected to the midpoint of the battery 60.

The completion of the circuit just traced effects energization of the indicating relay PA for a moment, and such momentary energization of this relay PA to the right with the lever L in the neutral position closes a pick up circuit for the relay EI which may be traced as follows:—beginning at the positive side B of a suitable battery, front contact 220 of relay PA, polar contact 221 of this same relay, wires 222 and 223, winding of the relay EI, wires 224 and 225, neutral contact 212 of the lever L, to the common return wire C. With the relay EI once picked up it is stuck up through the following stick circuit:—elements B, 226, 227, 223, EI, 224, 225, 202 to common wire C, back to the battery. With the relay EI in its energized condition the indicator EL is energized through the following circuit:—beginning at the terminal B of a suitable battery, front contact 228 of the relay EI, wire 229, indicating lamp EL, to the common wire C connected to the other side of said battery.

The operator is thus informed that the approaching train has entered upon the track circuit containing track relay 3T. It should be remembered that the indicating lamp EL will remain illuminated so long as the dispatcher does not move the lever L. If, however, the dispatcher moves the lever L from the neutral position momentarily and then returns it to the neutral position shown or moves it to either extreme position, the stick circuit for the relay EI is momentarily broken and this relay EI again assumes its de-energized position.

Let us assume that the dispatcher wishes the train in question to continue its west-

ward movement into the main track of the passing siding, and in order to do so moves the lever L in a clockwise direction so that the contacts 71 and 83 of this lever engages 5 the stationary contacts 95 and 96, respectively. The engagement of the contact 71 with the stationary contact 95 completes an energizing circuit for the control relay Z which may be traced as follows:—beginning at the 10 battery 75, wire 76, lever contact 71, wires 70 and 69, winding of the relay LR, wires 10, 10' and 85, front contact 98 of the relay OS, wire 99, winding of the control relay Z to the common return wire C connected to the 15 midpoint of the battery 75. It should be noted that energization of the line relay LR did not cause the relay EI to be picked up, because the circuit for the relay EI is broken at the lever contact 212, as is also the circuit 20 for the relay PA at the lever contact 211. The completion of the circuit for the control relay Z just traced causes the neutral contacts of the relay Z to pick up and causes the polar contacts to remain in the right hand 25 position shown. Since the switch machine SM already assumes the main track position the energization of the control relay Z will not affect the switch machine SM. The picking up of the neutral contact 100 of the relay 30 Z will however complete an energizing circuit to the signal mechanisms of the signal 1 which may be traced as follows:—beginning at the terminal B of a suitable source of current, front contact 100 of the relay Z, wire 35 101, polar contact 102 of the same relay, wire 103, contact 104—105 of the switch machine SM, wire 106, signal mechanisms of the signal 1 (not specifically shown), wire 107 front contact 108 of the home relay 1H, to the common 40 return wire C connected to the other terminal of said source. With this circuit completed the signal 1 will assume its clear proceed condition. In this connection it is desirable to point out that the polar home relay 45 1H is in practice controlled in accordance with the occupancy of the detector track circuit containing relay 2DT and the condition of occupancy of the two blocks next in advance thereof, and controls these three position 50 signals 1 and 1^a accordingly, as shown in my prior application above mentioned. The train in question may thus proceed in a westwardly direction, and if the operator has 55 acted immediately upon the illumination of the lamp EL and has allowed the signal 1 to clear before the train reached the signal 3, the train has not been restricted.

When the train in question passes the signal 1 and treads upon the detector track circuit the detector track relay 2DT, is de-energized, and thereby due to opening of the contacts 50 and 56 effects de-energization of the relay OS, the de-energization of which causes the control relay Z to be stuck up through 60 the following stick circuit:—beginning at the

positive terminal of the battery 60 polar contact 61 of the relay Z, wire 62, neutral contact 63 in the raised position, wire 110, contact 98 of the relay OS in its retractive position, wire 99, winding of the control relay 70 Z, common return wires C and through back contact 72 and wire 73 to the midpoint of the battery 60. The flow of current in the circuit just traced is of the same polarity as that formerly transmitted from the tower DO 75 so that the control relay Z will remain in the right hand energized position. Dropping of the relay OS breaks the line circuit at the contact 98 but connects the line wire 10 to the wire 66 through contact 65, but this circuit is 80 open at the contact 208 of the relay Z, so that the line circuit from the dispatcher's office at the distant track switch has been broken. The opening of the line circuit, as just mentioned, de-energizes the line relay LR at the 85 dispatcher's office, and causes the following circuit to be completed for the indicating lamp 4:—beginning at the positive terminal of the battery 75, wire 76, contacts 95—71, wires 70 and 112, back contact 113 of the line 90 relay LR, wire 114, lamp 4, wires 115 and 116, contact 96—83 of the lever L, wire 84 to the common return wire C connected to the midpoint of battery 75. The lamp 4, will for obvious reasons, remain illuminated so long as 95 the train in question occupies the detector track circuit, after which the lamp 4 is again extinguished.

Let us now consider the movement of a train in the same direction which the dispatcher after being informed of its approach upon the track circuit containing track relay 3T, may decide to direct into the siding of the passing siding shown. The approach of this train upon the track circuit containing 100 track relay 3T will effect illumination of the indicating lamp EL at the dispatcher's office for reasons heretofore given. Let us assume that the dispatcher has decided that this train shall take the siding and not the main track. 105 The dispatcher will therefore move the lever L in a counterclockwise direction so as to cause the control relay Z to assume its dotted energized position, this because the line wire 10 is now connected to the negative end of 110 the battery 75, thus operating the switch machine SM to the take-siding position.

As the switch machine is operated from one to the other extreme position the energizing circuit for the relay WP is broken 115 at the switch machine contact 47 and a similar circuit applying current of reverse polarity to the relay WP is completed when the switch machine has completed its operating stroke. This of course causes de-energization of the relay WP during the period of operation of the switch machine and upon dropping of relay WP causes momentary dropping of the relay OS, and in turn momentary flashing of the indicating lamp 4; 120 125 130

and similarly picking up of relay WP causes momentary dropping of relay OS, which in turn causes momentary dropping of relay LR and momentary flashing of the indicating lamp 4.

The switch machine SM now having assumed its reverse position and the control relay Z is also assuming the reverse position permits the take siding signal 1^a to be cleared through the following circuit:—beginning at the terminal B of a suitable source of current, front contact 100 of the control Z wire 101, polar contact 102 assuming the dotted position, wire 129, contacts 104—131, wire 132, control mechanism of the signal 1^a, wire 133, to the common return wire C connected to the other terminal of said source. In this connection it is desired to point out that this circuit may also include the front contact of a home relay controlled in accordance with traffic conditions over the siding, in the event that the siding is also track circuited. It is also desired to point out that the signals 1 and 1^a and 3 shown are preferably 3 position signals and have been thus conventionally illustrated, although the control circuits shown, illustrate only how they may be operated to two different positions.

The arrangement shown and described thus permits a switch machine and signals to be controlled over a single line circuit, over which the response of the switch machine to its control may be indicated, the approach of a train at a distant point, and the passage of a train over a detector track circuit may be indicated over this same line circuit, and in which the passage of the train by the two different points is distinctively indicated by two different indicating lamps. In this connection it should be noted that the passage of a train over the detector track circuit containing relay 2DT is never indicated by the indicating lamp 15, because no train is permitted to pass over this detector track circuit unless either the signal 1 or signal 1^a is clear, and this is possible only with the control lever L in an extreme position.

It may, by way of explanation, be pointed out here that if the lever L in the tower DO is in its middle neutral position the dropping of the relay EA will cause momentarily dropping of the relay EX, in the same manner as already described, and momentarily dropping of the relay EX will apply a positive potential to the line wire 10 and relay PA, providing the usual directional stick relay 2S of the signal 2 is not up as it would be if the relay EA had dropped by a departing train, through the following circuit:—beginning at the positive side of battery 60, wire 200, back contact 201 of the relay EX, wire 202, front contact 203 of the relay WA, wire 204, back contact 205 of the directional stick relay 2S, wires 206 and 207,

back contact 208 of the relay Z, wire 64, front contact 65 of the detector track relay 2DT, wire 66, back contact 67 of the relay OS (this relay now being de-energized because its energizing circuit is open at the front contact 54 of the relay EX) wire 68, line wire 10, wire 209, winding of the polar relay PA, wire 210, lever contact 211 to the common return wire C, connected to the neutral point of battery 60 through back contact 72 of the relay OS. This momentary completion of this circuit energizes the polar relay PA toward the right for an instant and in so doing picks up and sticks up the relay EI through circuits readily traced in the drawing. With the east indicating relay EI in the dispatcher's office in its energized condition the circuit for the east indicating lamp EL is closed so that this lamp will remain energized until the dispatcher wishes to extinguish the same. This may be done by moving the lever L from its neutral position momentarily thereby breaking the stick circuit for the stick relay EI at the contact 212.

In the same way as just explained in connection with a train approaching from the east, the approach of a train from the west is indicated at the indicating lamp WL on the dispatcher's miniature track layout by reason of the indicating stick relay WI being stuck up in response to a negative impulse received by the polar relay PA due to momentary dropping of the relay WX at the distant siding, this dropping of the relay WX applying negative potential to the line circuit 10 momentarily. For convenience, the corresponding contacts and wires for this later circuit for indicating the approach of a train from the west have been given like reference numbers with the distinctive exponents "one" as those of the circuit for indicating the approach of a train from the east just traced.

If the relay WP is omitted, as it may be when the switch machine operation is not to be indicated, the wires 53 and 57 would be connected together.

Although the invention has been shown applied to a track layout including a track switch, and wherein the approach of a train within say one mile of such track switch from either direction is indicated it is desired to be understood that the invention may in like manner be applied in the rear of an electrically operated derail located at a railroad crossing and the dispatcher may by this application of the invention be able to get information over the same line circuit used for controlling the derail as to the approach of a train, so that he may remove the derail if traffic conditions are safe and permit clearing of the signals associated with such derail. In other words, substantially the same circuit arrangement, modified only in a man-

ner as obvious to those skilled in the art of railroad signaling, may be used for controlling a derail at a railroad crossing and to indicate the approach of a train within, say one mile, of such derail, all substantially as shown in the accompanying drawings exemplifying one embodiment of the invention.

Further, it is desired to point out that instead of including the contacts 56 in the wire 57 they may be included in the wire 53, in which event the contacts 50 in the energizing circuit of the relay WP may be omitted. Also in the event the contacts 50 are omitted, the contacts 56 may be included in the wire 51.

Having thus shown and described one specific embodiment of the invention and having shown many of the devices forming parts of the novel combinations, conventionally, it is desired to be understood that this has been done for the purpose of simplifying the description of the invention, and has not been done for the purpose of illustrating the scope of the invention nor the exact construction preferably employed in practicing the same; and it is further desired to be understood that various changes, modifications and additions may be made to adapt the invention to the particular problems encountered in practicing the same, all without departing from the scope of the invention or the idea of means underlying the same, except as demanded by the scope of the following claims.

What I claim is:—

1. In a train dispatching system of the signal indicating type, the combination with a single line circuit and associated apparatus for controlling a distant wayside signal and indicating at the dispatcher's office the passage of a train by such signal, and means for distinctively indicating over the same line circuit the approach of a train toward said signal when such approaching train has come within vision of the next signal in the rear of such signal.

2. In a train dispatching system of the signal indicating type, the combination with a simple line circuit and associated apparatus for controlling a distant wayside signal and indicating at the dispatcher's office the passage of a train by such signal by the flow of current transmitted from a source at the dispatcher's office and means for distinctively indicating over the same line circuit the approach of a train toward said signal from a considerable distance by the flow of current from a source at said signal.

3. A train dispatching system of the signal indicating type comprising, a single line circuit extending from a local dispatcher's office to a distant control point having signals adjacent thereto, a control relay adjacent said signals controlled over said line circuit by energy from said dispatcher's office through suitable lever contacts operable by the dispatcher, a signal lamp energized when

said line circuit is broken in response to the passage of a train by such signals, and another signal lamp energized in response to energization of said line circuit from a source of current at said distant point to indicate the approach of a train toward said point.

4. A train dispatching system of the signal indicating type comprising, a single line circuit extending from a local dispatcher's office to a distant control point having signals adjacent thereto, a control relay adjacent said signals controlled by energy from said dispatcher's office through suitable lever contacts operable by the dispatcher, a signal lamp energized when said line circuit is broken as, for instance, in response to the passage of a train by such signals, and two other signal lamps respectively energized in response to the polarity of current applied to said line circuit at said distant point, said line circuit being energized with one polarity when there is a train approaching from one direction and being energized by the opposite polarity when there is a train approaching in the opposite direction.

5. A train dispatching system of the signal indicating type comprising, a single line circuit extending from a local dispatcher's office to a distant control point having signals adjacent thereto, a control relay adjacent said signals controlled by energy transmitted over said line circuit from said dispatcher's office through suitable lever contacts operable by the dispatcher, a signal lamp at the dispatcher's office energized when said line circuit is broken in response to the passage of a train by such signals, and two other signal lamps respectively energized in response to the polarity of current applied to said line circuit at said distant point, one of which lamps if energized indicates that there is a train approaching from one direction and the other lamp of which if energized indicates that there is a train approaching from the other direction.

6. A train dispatching system of the wayside signal indicating type comprising, a simple line circuit extending from a local dispatcher's office to a distant way station control point at which signals are located, a three position polar control relay at said way station connected to said line circuit and energized to one position or the other depending on the polarity of current applied to said line circuit at said dispatcher's office, a signal lamp at said office illuminated when said line circuit is energized from the dispatcher's end but is opened by means for opening the same in response to a train passing said signals, a second lamp at said dispatcher's office energized if there is a train approaching said signals from the one direction and in so doing momentarily applies positive potential to said line circuit at said way station, and a third lamp at the dispatcher's office energized if

there is a train approaching said signals from the opposite direction and in so doing momentarily applies negative potential to said line circuit.

7. A train dispatching system of the way-side signal indicating type comprising, a simple line circuit extending from a local dispatcher's office to a distant way station control point at which signals are located, a three position polar control relay at said way station connected to said line circuit and energized to one position or the other depending on the polarity of current applied to said line at said dispatcher's office, circuits for controlling said signals in accordance with the conditions of said control relay, an indicating lamp at the dispatcher's office energized when a lever in said office is moved from normal and assumes a position to cause current to flow in said line circuit from a source at said office but there is no such current flowing due to the fact that said line circuit is open, means for opening said line circuit at the way station end when a train passes one of said signals, means for energizing said line circuit from the way station end if there is a train approaching said signals, and another indicating lamp at the dispatcher's office illuminated in response to energization of said line circuit from the source at said way station.

8. A train dispatching system of the way-side signal indicating type comprising, a simple line circuit extending from a local dispatcher's office to a distant way station control point at which signals are located, a three position polar control relay at said way station connected to said line circuit and energized to one position or the other depending on the polarity of current applied to the line circuit at said dispatcher's office, circuits for controlling said signals in accordance with the conditions of said control relay, an indicating lamp at the dispatcher's office energized when a lever in said office is moved from normal and assumes a position to cause current to flow in said line circuit from a source at said office but there is no such current flowing due to the fact that said line circuit is open, means for opening said line circuit at the way station end when a train passes one of said signals, means for energizing said line circuit from the way station end by a polarity when there is a train approaching depending on the direction from which said train is approaching, and two indicators in said dispatcher's office one of which manifests the approach of a train in one direction and the other of which manifests the approach of train in the other direction toward said signals in response to the polarity of energization of said line circuit from a source at said way station if said lever is in its normal position.

9. A train dispatching system of the way-side signal indicating type comprising, a distant track switch, a power operated switch

machine for operating said track switch, a control relay for controlling said switch machine, a simple line circuit for controlling said control relay from a local source of current at a local dispatcher's office, and means for indicating the passage of a train over said switch by energy from the same source and indicating the approach of a train toward said switch from an appreciable distance over the said line circuit by a source of current located at said switch machine.

10. A train dispatching system of the way-side signal indicating type comprising, a distant track switch, a power operated switch machine for operating said track switch, a control relay for controlling said switch machine, a simple line circuit for controlling said control relay from a local source of current at a local dispatcher's office, and means for distinctively indicating by separate indicators the passage of a train over said switch, the approach of a train from one direction toward said switch and the approach of a train from another direction toward said switch over the same simple line circuit.

11. In a railway traffic controlling system, a local office, a distant traffic controlling device, means for controlling said distant traffic controlling device including a simple line circuit connecting said office and traffic controlling device and a source of current at said dispatcher's office, and means for continuously indicating at said office the approach of a train toward said traffic controlling device over the same line circuit and including a source of current located at said traffic controlling device.

12. A train dispatching system by the way-side signal indicating type comprising, a distant track switch, a power operated switch machine for operating said track switch, a control relay for controlling said switch machine, a simple line circuit for controlling said control relay from a local source of current at a local dispatcher's office, an approach relay and an energizing circuit therefore extending a considerable distance along the track for locking said switch machine against operation by said control relay if there is a train approaching within said distance, and means including said approach relay for indicating at said tower the approach of a train toward said switch machine at said considerable distance.

13. In a train dispatching system; the combination with a line wire and a common return wire each connecting a local dispatcher's office and a distant signal location; of a line relay and a polar approach indicating relay in said office; a lever in said office which may assume an intermediate or either of two extreme positions, and which if in its intermediate position connects said polar indicating relay between said line wire and said return wire, if in one extreme position con-

nects said line relay in series with a source of one polarity and between said line wire and said return wire, and if in the other extreme position connects said line relay in series with a source of the reverse polarity and between said line wire and said return wire; a polar control relay at said distant signal for controlling such distant signal energized in accordance with the polarity of the source of current connected to the line and return wire; means effective if said control relay is de-energized for applying a source of current between said line and return wire at said signal in response to the approach of a train the polarity of which depends upon the direction from which such train is approaching to effect energization of said polar relay in a corresponding direction; a normally closed contact in series with said control relay open when there is a train passing said signal; and three indicating lamps in said office one illuminated when said line relay is de-energized with said lever in one of its extreme positions, one illuminated when said polar relay is energized in one direction and the other illuminated when said polar relay is energized in the other direction.

14. In a train dispatching system; the combination with a line wire and a common return wire each connecting a local dispatcher's office and a distant signal location; of a polar approach indicating relay in said office; a lever in said office which may assume an intermediate or either of two extreme positions, and which if in its intermediate position connects said polar indicating relay between said line wire and said return wire, and if in either extreme position connects said line relay in series with a source of one polarity and between said line wire and said return wire, and if in the other extreme position connects said line relay in series with a source of the reverse polarity and between said line wire and said return wire; a polar control relay at said distant signal for controlling such distant signal energized in accordance with the polarity of the source of current connected to the line and return wire; means effective if said control relay is de-energized for applying a source of current between said line and return wire at said signal in response to the approach of a train the polarity of which depends upon the direction from which such train is approaching to effect energization of said polar relay in a corresponding direction; and two indicators controlled by said polar indicating relay one rendered active when said polar indicating relay is energized in one direction and the other of which is rendered active when said polar indicating relay is energized in the other direction.

15. In a train dispatching system, the combination with a line circuit connecting a dispatcher's office and a distant signal includ-

ing a control relay connected in series in said circuit at the signal end of said circuit and a manually operable lever having a contact connected in series with a source of current at the office end of said circuit, of another contact on said lever closed when said first mentioned contact is open and which if closed includes an indicating relay in said circuit at the office end of said circuit, means effective if said control relay is in its de-energized condition and there is a train approaching said signal for including a source of current in said line circuit at said signal end of said circuit to energize said indicating relay, and an indicator controlled by said indicating relay.

16. In a train dispatching system, the combination with a line circuit connecting a dispatcher's office and a distant signal including a control relay connected in series in said circuit at the signal end of said circuit and a manually operable lever having a contact connected in series with an indicating relay at the office end of said circuit, of another contact on said lever closed when said first mentioned contact is open and which if closed includes a source of current in series with said indicating relay and line circuit at said office end, means effective if said control relay is de-energized for energizing said indicating relay from a source of current located at said signal location.

In testimony whereof I affix my signature.

DISCLAIMER

1,794,567. -- *Sedgwick N. Wight*, Rochester, N. Y. TRAIN-DISPATCHING SYSTEM FOR RAILROADS. Patent dated March 3, 1931. Disclaimer filed February 16, 1934, by the assignee, *General Railway Signal Company*.

Hereby enters this disclaimer to claims 1, 11, and 12 of said Letters Patent, which are in the following words, to wit:

"1. In a train dispatching system of the signal indicating type, the combination with a single line circuit and associated apparatus for controlling a distant wayside signal and indicating at the dispatcher's office the passage of a train by such signal, and means for distinctively indicating over the same line circuit the approach of a train toward said signal when such approaching train has come within vision of the next signal in the rear of such signal."

"11. In a railway traffic controlling system, a local office, a distant traffic controlling device, means for controlling said distant traffic controlling device including a simple line circuit connecting said office and traffic controlling device and a source of current at said dispatcher's office, and means for continuously indicating at said office the approach of a train toward said traffic controlling device over the same line circuit and including a source of current located at said traffic controlling device.

"12. A train dispatching system by the wayside signal indicating type comprising a distant track switch, a power operated switch machine for operating said track switch, a control relay for controlling said switch machine, a simple line circuit for controlling said control relay from a local source of current at a local dispatcher's office, an approach relay and an energizing circuit therefore extending a considerable distance along the track for locking said switch machine against operation by said control relay if there is a train approaching within said distance, and means including said approach relay for indicating at said tower the approach of a train toward said switch machine at said considerable distance."
